US00D824365S

(12) **United States Design Patent** (10) **Patent No.:** **US D824,365 S**
(45) **Date of Patent:** **** Jul. 31, 2018**

(54) **PORTABLE SPEAKER**

(71) Applicant: **Skullcandy, Inc.**, Park City, UT (US)

(72) Inventors: **David G. Vogt, Jr.**, Salt Lake City, UT (US); **Peter M. Kelly**, Park City, UT (US); **Jason Luthman**, Park City, UT (US)

(73) Assignee: **Skullcandy, Inc.**, Park City, UT (US)

(**) Term: **15 Years**

(21) Appl. No.: **29/546,082**

(22) Filed: **Nov. 18, 2015**

(51) LOC (11) Cl. **14-03**

(52) U.S. Cl. **USPC D14/214**

(58) **Field of Classification Search**

USPC ..... D14/167, 168, 170-172, 188, 194-196, D14/204, 207, 209.1, 210-216, 219, 221, D14/222, 224, 239, 496; 181/143, 144, 181/147, 148, 150, 153, 157, 198, 199; 381/300-303, 306, 332, 333, 336, 345, 381/361-364, 386-388; 369/6-12 CPC B60R 11/0217; G06F 1/1688; G10K 9/22; G10K 11/004; H03F 1/327; H04M 1/03; H04M 1/035; H04N 5/642; H04N 21/4852; H04R 1/02; H04R 1/06; H04R 1/021; H04R 1/025; H04R 1/026; H04R 1/028; H04R 1/105; H04R 1/323; H04R 1/403; H04R 1/2803; H04R 1/2834; H04R 5/02; H04R 7/20; H04R 9/06; H04R 9/025; H04R 2201/021; H04R 2400/00; H04R 2400/07; H04R 2499/11; H04R 2499/13; H04R 2499/15; H04S 3/00; H04S 7/30

(57) **CLAIM**

The ornamental design for a portable speaker, as shown and described.

DESCRIPTION

FIG. 1 is a top, front and right side perspective view of a portable speaker, embodying our new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown are included for the purpose of illustrating portions of the portable speaker that form no part of the claim.

1 Claim, 6 Drawing Sheets
